UNITED STATES PATENT OFFICE

MARCUS CHARLES INMAN HUNTER, OF KEW GARDEN, AND FRANCIS LEONARD FLETCHER, OF HARLESDEN, ENGLAND, ASSIGNORS TO GENERAL ELECTRIC COMPANY, A CORPORATION OF NEW YORK

ELECTRIC SWITCHING APPARATUS

Application filed December 22, 1928, Serial No. 327,771, and in Great Britain January 19, 1928.

Our invention relates to electric switching apparatus, particularly of the type in which a main current controlling switch is mounted in a movable structure having isolating contacts which are adapted to engage cooperating contacts in a fixed structure. The object of our invention is the provision of switching apparatus of this character having improved means for covering the contacts of the fixed structure when the movable structure is withdrawn therefrom and for automatically operating the contact covering means in response to the movement of the movable structure.

15 Our invention will be better understood from the following description taken in connection with the accompanying drawings, and its scope will be pointed out in the appended claims.

20 Referring to the drawings, Fig. 1 is an elevation partly in section of a switching apparatus involving our invention with the movable structure thereof in its lowered or isolated position; Fig. 2 is an end view of 25 the same with parts broken away to more clearly show its construction; Figs. 3 and 4 are views similar respectively to Figs. 1 and 2 but with the movable structure in its raised or connected position.

25 The apparatus by which we have chosen to illustrate our invention comprises the three single pole oil switches 1, 2 and 3 secured together by the frame 4 to form a unitary movable structure. The several switches 1, 2 and 3 it will be noted are shown arranged with their insulator bushings 5 in alignment and resting on the top of each switch is the adapter 6 having a pair of upward extensions 7 arranged transversely of 40 the switch unit and having the isolating terminals 8 thereon. The terminals 8 connect by suitable conductors in the adapter with the terminals on the respective insulator bushings 5. It is to be understood that the use of adapters 6 is not essential to apparatus involving our invention since if desired the oil switches may be provided with insulator bushings spaced apart a sufficient distance to engage the cooperating isolating contacts.

45 Where, however, standard switches are to

be used the spacing of the insulator bushings of which is not great enough, we prefer to employ adapters such for example as those illustrated.

50 Cooperating with the movable structure thus described is the fixed structure 10 into which the former is arranged to be raised by means forming no part of the present invention and which in the interest of clearness has been omitted from the drawings. The structure 10 comprises a plurality of separate compartments 11 each containing an insulating liquid such as oil and having in its bottom the spout 12. The end of each spout is open and secured thereto is the hollow conical insulator 13. A fixed isolating terminal 14 is secured to the upper end of each insulator and to each of these terminals connects the bus bar or phase conductor 15.

55 For covering and protecting the fixed isolating contacts 14 when the movable structure is in its lowered position or when it is removed therefrom, as for example, for inspection or repair, we have provided shutter devices each comprising two segments 17 pivoted at 18 to the end spouts 12 and arranged when in closed position to make a tight connection with the respective spout openings. Each segment is shown provided 60 at one end with the projecting pin 19 by which it is operated. Adjacent the pins 19 and secured to the fixed structure 10 are the brackets 20 in which is slidably mounted the shutter operating rods or spears 22. Brackets 20 also have extensions 23, the purpose of 65 which presently will be described. At the lower end of each spear 22 there is pivoted the latch 24 which by means of the spring 25 connecting it with the spear is yieldingly held in the inoperative position when the main switches are in their lowered or disconnected position as shown in Fig. 1. When the main switch structure is raised from the position shown in Fig. 1 to that shown in Fig. 2, the projection 26 on the frame 4 engages the end 70 of the spear and raises it also. In this upward movement the upper end of the spear which preferably is somewhat pointed engages the pins 19 on the shutter segments and gives to the segments a rapid opening move- 75

100

- ment. The spear thereafter continues to slide between the pins upon continued upward movement of the main switch structure. In the initial upward movement of the spear the latch 24 engages the extension 23 and is rotated thereby against the spring 25 to a position such as that shown in Fig. 2 in which position it interlocks the spear and the projection 26. When the main switch structure is lowered away from the fixed structure, the spear, by reason of its being interlocked with the former structure is positively lowered therewith until the upper end of the spear passes beyond the pins 19 and the latch reaches the end of the extension 23 when it is swung by spring 25 away from the extension 26. The main switch structure may then be further lowered or entirely removed if desired without affecting the shutter operating mechanism. Upon the replacement of the main switch structure or the substitution of a similar one, the same when raised with the cooperating isolating contacts in proper alignment will engage and operate the spear in the manner already described. The two shutter segments of each pair naturally gravitate to the closed position. If it is deemed advisable, however, the force of gravity may be supplemented by the use of suitable springs attached to the segments. To prevent the spears from dropping out of their supporting brackets when the main switch structure is removed each is shown provided with the stop pin 27.
35. What we claim as new and desire to secure by Letters Patent of the United States, is:
1. Electric switching apparatus comprising fixed and movable structures having co-operating contacts, a contact covering device and an operating member therefor mounted on said fixed structure, and means insuring positive actuation of said operating member including a latching device carried by said operating member arranged to engage a portion of the movable structure when the same reaches a certain point in its movement toward the fixed structure and to become disengaged therefrom when it is withdrawn beyond a certain point.
  50. 2. Electric switching apparatus comprising fixed and movable structures having co-operating contacts, a contact covering shutter and an operating rod therefor mounted on the fixed structure, and means insuring positive actuation of said operating rod including a latching device arranged to interlock with a portion of the movable structure when the same reaches a predetermined point in its movement toward the fixed structure and to become released therefrom when the movable structure is withdrawn beyond a predetermined point.
  55. 3. Electric switching apparatus comprising a fixed contact supporting structure, a movable switch supporting structure having

a contact adapted to engage the contact of the fixed structure, a shutter device mounted on the fixed structure and arranged to cover the contact thereof, a shutter operating member arranged in the path of movement of a portion of the movable structure to be moved thereby, and means insuring positive actuation of said shutter operating member including a latch carried by said operating member arranged to be moved by its engagement with a portion of the fixed structure to a position interlocking with said portion of the movable structure.

4. Electric switching apparatus comprising a stationary contact supporting structure, a movable contact supporting structure, a contact covering device comprising a pair of shutter segments pivotally mounted on the stationary structure and engaging each other in the contact isolating position, a pin connected to each of said shutter segments, and a segment operating member slidably mounted within a guide on the stationary structure and arranged to be positively actuated by said movable structure, said segment operating member initially engaging said pins and subsequently passing between the same to cause opening of said shutters in opposite directions prior to movement of the movable contacts therethrough.

5. Electric switching apparatus comprising a fixed contact supporting structure, a movable contact supporting structure, a shutter adapted to cover the contacts of the fixed structure comprising a pair of segments pivoted to the fixed structure and having operating projections thereon, a spear permanently mounted on the fixed structure for limited longitudinal movement and arranged initially to engage said projections and move the segments to a position uncovering the contacts and subsequently to pass freely between the projections, said movable contact supporting structure having a disengageable connection with said spear.

In witness whereof, we have hereunto set our hands this 4th day of December, 1928.

MARCUS CHARLES INMAN HUNTER.
FRANCIS LEONARD FLETCHER.
